Primary Examiner—Bridget L Eland*(74) Attorney, Agent, or Firm*—Timothy D Evans(57) **CLAIM**

The ornamental design for a surgical collet, as shown and described.

DESCRIPTION

FIG. 1 is a top front perspective view of a surgical collet;

FIG. 2 is a left side elevational view thereof;

FIG. 3 is a right side elevational view thereof;

FIG. 4 is a top plan view thereof; and

FIG. 5 is a bottom plan view thereof.

FIG. 6 is a front elevational view thereof; and,

FIG. 7 is a rear elevational view thereof.

The outermost broken lines depicting the circles in FIGS. 1 and 6 represent the bounds of the claimed design while the broken lines depicted within the circles and the broken line depicting the arrow in FIGS. 1 and 6 and the remainder of the handpiece are directed to environment and are for illustrative purposes only; the broken lines form no part of the claimed design.
